UNITED STATES PATENT OFFICE

166,021

NECKTIE

Harold K. Birkestol, Arlington, Wash.

Application January 11, 1950, Serial No. 7,160

Term of patent 14 years

(Cl. D3—16)

To all whom it may concern:

Be it known that I, Harold K. Birkestol, a citizen of the United States, residing at Arlington, county of Snohomish, and State of Washington, have invented a new, original, and ornamental Design for a Necktie, of which the following is a specification, reference being had to the accompanying drawing, forming part thereof.

The figure is a view of a necktie, showing my new design.

I claim:

The ornamental design for a necktie, as shown.
HAROLD K. BIRKESTOL.
